ATTORNEYS

UNITED STATES PATENT OFFICE.

REBECCA GREENBERG, OF NEW YORK, N. Y.

QUILT COVER.

Application filed January 19, 1925. Serial No. 3,410.

To all whom it may concern:

Be it known that I, REBECCA GREENBERG, a citizen of the United States, and a resident of the city of New York, borough of Bronx, in the county of Bronx and State of New York, have invented a new and Improved Quilt Cover, of which the following is a full, clear, and exact description.

This invention relates to an improved fastening means for a quilt cover. An object of the invention is to provide a simple and efficient means for fastening a cover to a quilt so that the quilt and cover are permanently held in their proper relation.

Another object concerns the provision of a simple and efficient fastening means which can be very quickly and easily fastened and unfastened by the housewife.

The invention is illustrated in the drawings, of which—

Figure 1 is a plan view with a portion broken away showing the cover and the quilt connected together;

Fig. 2 is a section on the line 2—2 of Fig. 1;

Fig. 3 is a section on the line 3—3 of Fig. 1;

Fig. 4 is a section showing the fastening means unfastened;

Fig. 5 is a section through a loop member on the quilt; and

Fig. 6 is a perspective view of the loop and supporting plate.

The form of the invention shown in the drawings is a preferred form, although it is understood that modifications in the construction and arrangement of the parts and in the character of the materials used may be adopted without departing from the spirit of the invention as set forth in the appended claims.

In its general aspect the invention comprises means for fastening a quilt and a cover therefor together in a simple and efficient manner. In the use of quilts, especially babies' quilts, it is sometimes desirable to provide them with a cover which preferably extends completely across one side of the quilt and partly over the other side. In most cases the cover is held to the quilt by some sort of fastening means connecting the edges of the open side of the cover with a fastening element on the quilt.

My particular construction involves a number of loops fastened to the quilt, and a

plurality of straps fastened to the cover, these straps adapted to be passed through the loops and then bent back on themselves and provided with fastening elements to hold their ends down. In other words, when the fastening means are effective the straps on the cover are formed as loops which pass through loops on the quilt.

The particular details of the construction are those which I have found by actual practice to be most efficient in the development of the idea.

The preferred form of the invention includes a quilt 10 over which a cover 11 is disposed. This cover completely encloses the quilt on one side and extends partly over the other side of the quilt in the form of a narrow band 12, leaving an opening 13, through which the quilt can be observed in Fig. 1. Along the edge of the open portion of the cover I attach a plurality of straps 14 which are fastened to the edge of the band 12 in any suitable manner. Each strap is preferably provided with a fastener element, as shown in the drawings, in the form of a buttonhole 15. The band 12 adjacent each strap 14 is provided with a cooperating fastening element which is shown as being preferably a button 16. When the end of the strap 14, therefore, is bent back on itself to form a loop, the button 16 and the buttonhole 15 co-operate to hold the loop closed.

This loop of the strap 14 preferably passes through a metallic loop portion 17 on the quilt, there being one of the quilt loops fastened to the quilt adjacent each strap. Preferably the quilt loop is fastened to the quilt means of metal plates 18 provided with apertures 19 by means of which the plate can be sewed to the quilt. The plate is provided with struck-up ear portions 20 beneath which the shank of the metal loop 17 passes, as shown in Fig. 3. In order to fasten the cover to the quilt, it is merely necessary to pass the end of the strap through the metal loop 17 and then fasten the end of the strap back on the band 12 by means of the button and the buttonhole. Other fastening devices, of course, can be used having more than one buttonhole, and by having a plurality of buttons adjacent each metal loop the degree of fastening can be varied as desired, although this construction is not shown.

This device is simple and easy to apply to and remove from the quilt. It forms an efficient cover for the side of the quilt which it is desired to protect and yet exhibits substantially entirely one side of the quilt, as is desirable. The fact that a number of these fastening devices are disposed around the edges of the opening of the cover keeps the quilt and the cover from getting out of place with respect to each other and maintains a neat, uniform appearance at all times.

It is to be understood that instead of using buttons and buttonholes on the strap-
fastening device, snap fasteners or any other suitable type of fastener can be used, the inventor not wishing to limit herself to the particular type of fastening shown.

What I claim is:

1. A quilt cover, which comprises a fabric bag having one side partially open, a plurality of straps disposed along the edges of the open side, fastening means on the straps whereby they can be held detachably in the

form of a loop, and means on the quilt to engage with said loops to hold the quilt and the cover together.

2. A quilt cover, which comprises a fabric bag having one side partially open, a plurality of straps disposed along the edges of the open side, fastening means on the straps whereby they can be held detachably in the form of a loop, and a plurality of loops attached to the quilt adjacent the straps and adapted to engage therewith.

3. A quilt cover, which comprises a bag of fabric having an open side, a strap connected to the edge of the bag adjacent the opening, a button on the bag adjacent the strap, said strap on its free end having a buttonhole, said strap adapted to be bent back to form a loop whereby the button and the buttonhole will co-operate, a quilt to be held within the bag, and a metal loop fastened to the quilt and adapted to receive the strap.

REBECCA GREENBERG.
